ABRAHAM GREENSTEIN, OF NEW YORK, N. Y.

DUPLICATE SALES-CHECK TAG.

1,199,692.

Specification of Letters Patent. Patented Sept. 26, 1916.

Application filed September 20, 1915. Serial No. 51,546.

To all whom it may concern:

Be it known that I, ABRAHAM GREENSTEIN, a citizen of the United States, and a resident of the city of New York, borough of Manhattan, in the county and State of New York, have invented a new and Improved Duplicate Sales-Check Tag, of which the following is a full, clear, and exact description.

- 10 This invention relates to shipping devices and has particular reference to improved facilities for the billing and delivery of packages or other articles in or from retail stores or the like.
- 15 In the ordinary practice in the delivery system of a large business house, the salesman or clerk is provided with a salesbook with sales slips arranged therein in duplicate and adapted for use of carbon paper or 20 the like for making a duplicate record on the second sales slip while the original record is being written on the first slip. The original or first sheet or slip is sent to the office and the duplicate slip is torn off and 25 sent with the package. When the package is wrapped, the duplicate slip is folded or rolled and slipped within the package or beneath the cord, and when a considerable number of such packages have accumulated, 30 an employee pastes the loose slips upon tags which are then tied upon the packages. Among the disadvantages of this present system may be noted, first, that the identification slips become either torn, misplaced 35 or lost in the interval between the application thereof to the package and the pasting operation; secondly, much time is lost in the pasting of the slips upon the packages in addition to the inconvenience and delay in 40 cident to the loss of the slips; and thirdly, the expense of delivery is very much increased by reason, not only of additional clerk hire, but because of the other inconveniences above referred to.
- 45 Among the objects of this invention, therefore, is to provide a combination duplicate salesbook and check tag having all of the facilities or advantages of the duplicating or manifolding system now in use and 50 without the several disadvantages referred to above.

More definitely stated, the invention comprises a duplicate salesbook having the usual original record slips and beneath 55 each of which is a leaf or sheet adapted to receive the duplicate record, but which leaf

or sheet is formed of strong tough paper or its equivalent and having a hole at either or both ends whereby the duplicate sheet may be treated as a tag and readily adapted to 60 be tied to the package coincidentally with the wrapping of such package.

With the foregoing and other objects in view, the invention consists in the arrangement and combination of parts hereinafter 65 described and claimed, and while the invention is not restricted to the exact details of construction disclosed herein, still for the purpose of illustrating a practical embodiment thereof, the figure is a face view 70 in perspective of a duplicate salesbook made in accordance with this invention, fragments of the original sheet being torn off to disclose the tag sheet.

The numeral 10 indicates a salesbook having first or original sheets or slips 11, and second or duplicate sheets 12 arranged in pairs and connected to the stub 13 by weakened lines 14 as is common in this class of devices. The illustration covers a book having original sheets 11 printed or arranged in two parts 11^a and 11^b, these two parts being connected by a weakened line 15. It will be understood, however, that the specific arrangement of these several parts has 85 no immediate bearing upon the present invention, but such parts are shown in order to set forth the characteristic features or advantages of the real invention. On the second or duplicate sheet there are formed two parts 12^a and 12^b corresponding in form and arrangement of printed matter to the similar parts of the first sheet. The parts 12^a and 12^b, however, are printed on strong tough and heavier paper suitable for use as 95 tags to be tied upon the bundles. These parts are connected by a weakened line 15' for easy separation. The tag 12^a is provided with a hole 16 and the shorter tag 12^b is provided with a hole 17, either tag of 100 which is adapted to be readily tied to the bundle coincidentally with the original wrapping thereof without material loss of time or inconvenience.

By way of further explanation of the 105 manner of using the invention in a C. O. D. transaction, the original thin slip 11^a goes to the auditor, and the original thin slip 11^b is sent to the C. O. D. clerk at the office. The tag slip 12^a is tied to the package for collection 110 and the tag 12^b is wrapped within the package where it may be found for future

identification should it be necessary to duplicate the tag 12^a. The tag slip 12^a being longer than the slip 12^b facilitates the handling of the packages with reference to whether the transaction is C. O. D. or a paid or charged transaction. In practice, when the sale is made for cash or charge, the original thin slip 11^a is sent to the auditor as before described; and the shorter slip 11^b is held by the packer as his voucher. The longer tag slip 12^a is put inside of the package and the shorter tag slip 12^b is tied as a shipping tag. This tag on removal from the package by the deliveryman is received on the back by the recipient of the package and is returned by the deliveryman or driver to the office to prove delivery.

I am aware that duplicate salesbooks are in common use in which original and duplicate records are made simultaneously by a salesman, the several checks thus produced being adapted to be sent to different departments of the establishment or utilized for different purposes. I am also aware that it is a common expedient to provide a shipping tag to carry the name and address of the addressee of a package or parcel to which the tag is adapted to be secured. I believe, however, it is new with me to construct or provide a salesbook having the characteristics and advantages set forth herein and specifically claimed below.

I claim:

1. As a new article of manufacture, a manifold sales check and shipping tag book, comprising a plurality of alternate thin and tough and heavy sheets bound together at one end and having weakened lines adjacent the bound ends, and weakened lines intermediate of their ends forming each sheet into two parts, each part having provision for address of purchaser and for memorandum of sale and amount of same and provided with indications designating the character of the transaction, the parts of the thin and heavy sheets corresponding in size and having the same and registering matter thereon, the thin sheets being adapted to receive the original record of a transaction and forming sale checks, and the tough and heavy sheets receiving the duplicate of the transaction and provided with an opening to permit one of its parts to be tied to a package to serve as a shipping tag, and a receipt for the delivery of the package the other part of said sheet serving as an identification card.

ABRAHAM GREENSTEIN.

Witnesses:

LEO C. MACK,
A. STERNBERG.

acter of the transaction, the parts of the thin and heavy sheets corresponding in size and having the same and registering matter thereon, the thin sheets being adapted to receive the original record of a transaction and forming sale checks, and the tough and heavy sheets receiving the duplicate of the transaction and provided with an opening to permit one of its parts to be tied to a package to serve as a shipping tag, and a receipt for the delivery of the package the other part of said sheet serving as an identification card.

2. As a new article of manufacture, a manifold sales check and shipping tag book, consisting of a plurality of alternate thin and tough and heavy sheets bound together at one end and having weakened lines adjacent the bound ends, and weakened lines intermediate of their ends forming each sheet into two parts of unequal size, each part having provision for address of purchaser and for a memorandum of sale and amount of same and provided with indications designating the character of the transaction, the parts of the thin and heavy sheets corresponding in size and having the same and registering matter thereon, the thin sheets being adapted to receive the original record of transaction and forming sale checks and the tough and heavy sheets receiving the duplicate of the transaction, and each part provided with an opening whereby to permit either part to be tied to a package according to the nature of the transaction, to serve as a shipping tag for the same, and a receipt for the delivery of the package the other part of said sheet serving as an identification card.
